UNITED STATES PATENT OFFICE.

HILEND R. ROSE, OF POUGHKEEPSIE, NEW YORK.

COVERING FOR BRICK-HACKS.

SPECIFICATION forming part of Letters Patent No. 352,839, dated November 16, 1886.

Application filed November 23, 1885. Serial No. 183,824. (No model.)

To all whom it may concern:

Be it known that I, HILEND R. ROSE, a citizen of the United States, residing at Poughkeepsie, in the county of Dutchess and State 5 of New York, have invented certain new and useful Improvements in Coverings for Brick-Hacks; and I do hereby declare the following to be a full, clear, and exact description of the invention, such as will enable others skilled in 10 the art to which it appertains to make and use the same.

My invention relates to the coverings for brick-hacks; and the nature thereof consists in certain improvements in the construction of 15 the same, and novel combination of parts, hereinafter described and shown.

In the accompanying drawings, in which corresponding parts are designated by similar letters, Figure 1 is a side elevation. Fig. 2 is a 20 transverse vertical section, and Fig. 3 is a perspective view.

The saddle A is constructed of boards fastened together at right angles, and provided with strips B, of wood or iron, to strengthen 25 it and prevent the boards from splitting. These strips extend above the top of the saddle in such a manner as to form by their intersection a crotch or fork, which constitutes an angular receptacle for the reception of the 30 sides D D of the covering when they are not in use. These sides, which are made of canvas, leather, rubber, or some other suitable flexible material, are fastened to the saddle, and provided with rods d, of heavy wood or 35 iron, to keep them in place. The saddles thus

constructed are arranged to overlap, the one over the other, the entire length of the hack, thus giving strength to the covering throughout its length.

A covering such as described will require 40 less room than those now in use; it can easily and quickly be put over the hack or removed therefrom; it can be so placed that the top of the hack is covered while the sides thereof are exposed; it cannot be displaced by a sudden 45 gust of wind, and will protect the hack from top to bottom in all kinds of weather.

I am aware that a frame supporting a flexible covering has been described in United States Patent No. 314,457. 50

Having thus described my invention, I claim and desire to secure by Letters Patent—

1. A covering for brick-hacks, consisting of a series of saddles constructed of boards fastened together at right angles, and provided 55 with strips B, and weighted flexible sides, the one overlapping the other, as and for the purpose described.

2. The saddle provided with strips extending above it in such a manner as to form a 60 crotch or angular receptacle, in combination with weighted and flexible sides, as and for the purpose described.

In testimony whereof I affix my signature in presence of two witnesses.

HILEND R. ROSE.
